WITNESS:

ATTORNEY

UNITED STATES PATENT OFFICE.

JEREMIAH R. S. McCARTHY, OF FRANKLINVILLE, NEW YORK.

WELL-DRILLING APPARATUS.

Application filed April 12, 1923. Serial No. 631,604.

To all whom it may concern:

Be it known that I, JEREMIAH R. S. McCARTHY, a citizen of the United States, residing at Franklinville, in the county of Cattaraugus and State of New York, have invented new and useful Improvements in Well-Drilling Apparatus, of which the following is a specification.

This invention relates to improvements in well drilling apparatus and has for an object the provision of means whereby a number of wells may be drilled from a main station or main rig, means being provided whereby the drilling apparatus of each well may be either simultaneously or independently operated.

Another object of the invention is the provision of a novel form of beam jack, whereby a maximum amount of power may be obtained for the drilling operation.

Another object of the invention is the provision of a multiple drilling apparatus which is simple in construction and efficient and economical in operation.

With the above and other objects in view, the invention further includes the following novel features and details of construction, to be hereinafter more fully described, illustrated in the accompanying drawings and pointed out in the appended claims.

In the drawings:

Figure 1 is a plan view of a multiple well drilling apparatus constructed in accordance with the invention.

Figure 2 is a fragmentary side elevation of the main rig.

Figure 3 is a horizontal sectional view taken on a line with the main operating shaft.

Figure 4 is a side elevation of the guide pulleys.

Figure 5 is an elevation of a portion of one of the auxiliary rigs.

Figure 6 is a vertical central section of the same.

Figure 7 is a view on the line 7—7 of Figure 6.

Figure 8 is a perspective view of the beam jack shown in Figure 6.

Figure 9 is a fragmentary elevation illustrating the manner of mounting the beam jack.

Figure 10 is an elevation of one of the beam jack cable guides.

Figure 11 is a fragmentary vertical sectional view illustrating a modified form of the invention.

Figure 12 is a diagram illustrating the manner of running a telephone cable from the main to the auxiliary rigs.

Figure 13 is a detail view illustrating a telephone cable supporting means.

Referring in detail to the drawings wherein like characters of reference denote corresponding parts, the invention which is designed for the operation of drilling a number of wells simultaneously and for controlling the drilling operations from a single station, includes a main rig A and auxiliary rigs B. While two auxiliary rigs are illustrated, one or more may be operated from the main rig.

The main rig which may be substantially of the standard type includes a derrick 15, a crown pulley 16 and a drilling cable 17 which passes over the crown pulley. This drilling cable has connected thereto one end of a beam 18 and the latter is pivotally mounted as shown at 19. The opposite end of this beam is connected to one end of a pitman 20 and the opposite end of this pitman is connected to a crank arm 21 which is carried by a drive shaft 22. This shaft has mounted thereon a drive pulley 23 which is driven by means of a belt 24 from a suitable source of power.

Mounted in suitable bearings is a main operating shaft 25 and mounted for free rotation upon this shaft is a hoisting drum 26 around which the drilling cable 17 is wound after it passes over the crown pulley 16. The drum 26 is locked to or released from the shaft 25 by means of a clutch 27, the said clutch being connected by means of a rod 28 with a hand operated controlling lever 29. The hoisting drum 26 carries a brake drum 30 around which operates a brake band 31 for the purpose of controlling the operation of the drum 26. This brake band is connected by means of a rod or connection 32 with a hand lever 33.

Also mounted for free rotation on the shaft 25 is a bailing drum 34 and this drum like the drum 26 is provided with a brake

drum 35 which is engaged by a band 36 and controlled by a hand lever 37'. The bailing drum 34 is adapted to have wound thereon a sand line or bailing cable 37 which passes upward over a crown pulley 38 and is connected in the usual manner.

The shaft 25 has secured thereon a pulley 39 which is driven from a suitable source of power by means of a belt 40.

- 10 By means of the apparatus just described, the drilling and bailing operation of a well at the main rig A may be controlled and for the purpose of operating and controlling the operation of the auxiliary rigs B, the shaft 25 has mounted thereon for free rotation auxiliary hoisting drums 41 and auxiliary bailing drums 42. The drums 41 are controlled by clutches 43 which are similar to the clutches 27 previously described 20 and are further provided with brakes 44 of the character previously mentioned. The bailing drums 42 are similarly equipped with brakes 45 and are controlled by means of clutches 46. By this means all of the 25 hoisting drums may be locked with the shaft 25 and simultaneously operated, or they may be selectively operated as desired. This is also true of the bailing drums.

The hoisting drums 41 have wound thereover drilling cables 47 and these cables pass through guide yokes or pulleys 48 and around guide pulleys 49. They then pass through yokes or guide pulleys 50 and over crown pulleys 51 which are mounted at the 35 tops of the derricks 52 of the auxiliary rigs B.

The cables 47 pass downward through the derricks and are connected to one end of auxiliary or pony beams 53, the latter being pivotally mounted as shown at 54 upon suitable standards 55. These pony beams 53 are operated by jacks 56 which are pivotally mounted as shown at 57 and which are connected to the beams 53 by connecting 45 rods or pitmans 58. The jacks 56 are shown in detail in Figure 8 of the drawings and are substantially L-shaped, the arms of the jacks being connected by braces 59. The pitmans 58 may be adjustably connected to 50 the beams 53 and for this purpose the latter are provided with spaced openings 60.

The auxiliary beams 53 are operated from the crank arm 21 of the main rig A and for this purpose there is connected to this 55 crank arm, one end of a cable, rod or similar member 61. The opposite end of this member carries a ring 62 which in turn carries one or more rings 63, the number of the latter depending upon the number of auxiliary rigs B. The rings 63 are connected to members 64 of a character similar to the member 61, connection being effected by means of hooks 65. The opposite ends of the members 64 are connected to the jacks 60 65 of the auxiliary rigs. These jacks are

provided with spaced openings 66 so that an adjustment may be effected to regulate the degree of movement of the jacks and consequently the movement of the beams 53.

For the purpose of guiding the members 61 and 64 there is provided a plurality of cable guides C, which include a head 67 and legs 68 pivotally connected thereto. The head 67 has adjustably mounted therein a downwardly extending rod 69 which carries at its lower end a hook 70 for the reception of the members 61 and 64 so that the latter will be supported with a minimum amount of friction.

Also secured to the rings 63 are centering devices in the form of rods or cables 70. These rods or cables are detachably connected to the rings 63 and their outer ends are similarly connected to anchors 71. This form of connection permits of a backward 85 and forward movement of the members 61 and 64 during the drilling operation and maintains the adjacent connected ends of these members in proper relative position. In addition, either of the members 64 may 90 be disconnected to cut out the operation of either of the auxiliary rigs B, while the connected members 61 and 64 will retain their proper operative relation.

The bailing drums 42 have wound thereon 95 cables 72 which pass through yokes or pulleys 73 and around the pulleys 49 and through guide eyes or pulleys 74 and over crown pulleys 75, the latter being carried by the derricks of the auxiliary rigs B.

In Figure 11 there is illustrated a modified form of connection for the beams 53 of the auxiliary rigs. This comprises a branch cable 76 which extends from the member 64 and is connected as shown at 77 with the 105 beam 53, means being provided whereby this connection may be adjusted as necessary.

In Figures 12 and 13 there is illustrated means whereby a telephone line or cable may be connected between the main and auxiliary rigs. This comprises bracket arms 78 which are secured upon the upper threaded ends of the rods 69. These arms are provided with clamps 79 for holding the telephone wires, while the telephone stations 115 at the rigs A and B are indicated at S.

The invention is susceptible of various changes in its form, proportions and minor details of construction and the right is herein reserved to make such changes as 120 properly fall within the scope of the appended claims.

Having described the invention what is claimed is:—

1. A well drilling apparatus, a main rig 125 including a drilling cable, means whereby the main rig may be operatively connected to a source of power, an auxiliary rig also including a drilling cable, means operatively connecting the main and auxiliary rigs to 130

provide for simultaneous operation of the drilling cables and means whereby the main or auxiliary rigs may be independently operated.

5 2. In a well drilling apparatus, a main rig including a drilling cable and a bailing cable, means whereby the rig may be operatively connected to a source of power, an auxiliary rig also including a drilling 10 cable and a bailing cable, means operatively connecting the main and auxiliary rigs to provide for simultaneous operation of the drilling cables and bailing cables, means whereby said drilling cables may be independently operated and means for independently operating the bailing cables.

15 3. In a well drilling apparatus, a main rig including a drilling cable and a bailing cable, means whereby the rig may be operatively connected to a source of power, an auxiliary rig also including a drilling cable and a bailing cable, means operatively connecting the main and auxiliary rigs to provide for simultaneous operation of the 20 drilling cables and bailing cables, means whereby said drilling cables may be independently operated and means included in the main rig whereby the bailing cables may be independently operated.

25 4. In a well drilling apparatus, a main rig including a drilling cable and a bailing cable, means whereby the rig may be operatively connected to a source of power, an auxiliary rig also including a drilling cable and a bailing cable, means operatively connecting the main and auxiliary rigs to provide for simultaneous operation of the 30 drilling cables and bailing cables, means whereby said drilling cables may be independently operated and means included in the main rig whereby the drilling cables and bailing cables may be simultaneously or independently operated.

35 5. In a well drilling apparatus, a main rig including a pivotally mounted beam, means whereby the main rig may be operatively connected to a source of power, auxiliary rigs also including pivotally mounted beams, flexible members connecting the main rig and the beams of the auxiliary 40 rigs, spaced means located between the main and auxiliary rigs for supporting and guiding said members and means for controlling the operation of the rigs.

45 6. In a well drilling apparatus, a main rig including a pivotally mounted beam, means whereby the main rig may be operatively connected to a source of power, auxiliary rigs also including pivotally 50 mounted beams, flexible members connecting the main rig and the beams of the auxiliary rigs, spaced means located between the main and auxiliary rigs for supporting and guiding said members and means for controlling the operation of the rigs.

55 60 6. In a well drilling apparatus, a main rig including a pivotally mounted beam, means whereby the main rig may be operatively connected to a source of power, auxiliary rigs also including pivotally mounted beams, flexible members connecting the main rig and the beams of the auxiliary

rigs, spaced means including vertically adjustable anchor rods for supporting and guiding said members and means for controlling the operation of the rigs.

65

7. In a well drilling apparatus, a main rig including a drilling cable and a bailing cable, means whereby the rig may be operatively connected to a source of power, an auxiliary rig also including a drilling 70 cable and a bailing cable, means operatively connecting the main and auxiliary rigs to provide for simultaneous operation of the drilling cables and bailing cables, means whereby said drilling cables may be independently operated, said means embodying leg supported heads and anchor rods threadedly adjustable through said heads and means for controlling the operation of the rigs.

75

8. In a well drilling apparatus, a main rig including a drilling cable and a bailing cable, means whereby the rig may be operatively connected to a source of power, an auxiliary rig also including a drilling cable 80 and a bailing cable, means operatively connecting the main and auxiliary rigs to provide for simultaneous operation of the drilling cables and bailing cables, means whereby said drilling cables may be independently operated, said means embodying leg supported heads and anchor rods threadedly adjustable through said heads, wire supporting arms mounted upon said rods and means for controlling the operation of the rigs.

85

9. In a well drilling apparatus, a main rig including a pivotally mounted beam, means whereby the main rig may be operatively connected to a source of power, auxiliary rigs also including pivotally 90 mounted beams, flexible members connecting the main rig and the beams of the auxiliary rigs, centering devices located upon opposite sides of and having their inner ends connected to the flexible members, anchoring 100 means for the outer ends of said devices, means for supporting and guiding the flexible members and means for controlling the operation of the rigs.

95

10. In a well drilling apparatus, a main rig including a pivotally mounted beam, means whereby the main rig may be operatively connected to a source of power, auxiliary rigs also including pivotally 105 mounted beams, flexible members connecting the main rig and the beams of the auxiliary rigs, centering devices located upon opposite sides of and connected to the flexible members and means for controlling the operation 115 of the rigs.

110

In testimony whereof I affix my signature.
JEREMIAH R. S. McCARTHY.
